CLAIM

The ornamental design for ladder, as shown and described.

DESCRIPTION

FIG. 1 is a front view of the ladder, with the ladder shown in a retracted and partially folded position, showing my new design.

FIG. 2 is a front view thereof, with the ladder shown in a retracted and partially folded position.

FIG. 3 is a rear view thereof, with the ladder shown in a retracted and partially folded position.

FIG. 4 is a left side view thereof, with the ladder shown in a retracted and partially folded position.

FIG. 5 is a right-side view thereof, with the ladder shown in a retracted and partially folded position.

FIG. 6 is a top view thereof, with the ladder shown in a retracted and partially folded position.

FIG. 7 is a bottom view thereof, with the ladder shown in a retracted and partially folded position.

FIG. 8 is rear perspective view thereof, with the ladder shown in a retracted and partially folded position.

FIG. 9 is an enlarged detail view of area 9 of FIG. 1; with the ladder shown in a retracted and partially folded position.

FIG. 10 is an enlarged detail view of area 10 of FIG. 8; with the ladder shown in a retracted and partially folded position.

FIG. 11 is an enlarged detail view of area 11 of FIG. 8; with the ladder shown in a retracted and partially folded position.

FIG. 12 is an enlarged detail view of area 12 of FIG. 1; with the ladder shown in a retracted and partially folded position.

FIG. 13 is an enlarged detail view of area 13 of FIG. 6; with the ladder shown in a retracted and partially folded position.

FIG. 14 is a perspective view of the ladder of FIG. 1, with the ladder shown in a retracted, folded and closed position.

FIG. 15 is a front view thereof, with the ladder shown in a retracted, folded and closed position.

FIG. 16 is a rear view thereof, with the ladder shown in a retracted, folded and closed position.

FIG. 17 is a left-side view thereof, with the ladder shown in a retracted, folded and closed position.

FIG. 18 is a right-side view thereof, with the ladder shown in a retracted, folded and closed position.

FIG. 19 is a perspective view thereof, with the ladder shown in a retracted, folded and closed position.

FIG. 20 is a bottom view thereof, with the ladder shown in a retracted, folded and closed position.

FIG. 21 is a rear view thereof, with the ladder shown in a retracted, folded and closed position.

FIG. 22 is an enlarged detail view of area 22 of FIG. 14; with the ladder shown in a retracted, folded and closed position.

FIG. 23 is an enlarged detail view of area 23 of FIG. 21; with the ladder shown in a retracted, folded and closed position.

FIG. 24 is an enlarged detail view of area 24 of FIG. 21; with the ladder shown in a retracted, folded and closed position.

FIG. 25 is an enlarged detail view of area 25 of FIG. 21; with the ladder shown in a retracted, folded and closed position.

FIG. 26 is an enlarged detail view of area 26 of FIG. 14; with the ladder shown in a retracted, folded and closed position.

FIG. 27 is a perspective view of the ladder of FIG. 1, with the ladder shown in a partially extended and partially folded position.

FIG. 28 is a front view thereof, with the ladder shown in a partially extended and partially folded position.

FIG. 29 is a rear view thereof, with the ladder shown in a partially extended and partially folded position.

FIG. 30 is a left-side view thereof, with the ladder shown in a partially extended and partially folded position.

FIG. 31 is a right-side view thereof, with the ladder shown in a partially extended and partially folded position.

FIG. 32 is a top view thereof, with the ladder shown in a partially extended and partially folded position.

FIG. 33 is a bottom view thereof, with the ladder shown in a partially extended and partially folded position.

FIG. 34 is a rear perspective view thereof, with the ladder shown in a partially extended and partially folded position.

FIG. 35 is an enlarged detail view of area 35 of FIG. 27; with the ladder shown in a partially extended and partially folded position.

FIG. 36 is an enlarged detail view of area 36 of FIG. 34; with the ladder shown in a partially extended and partially folded position.

FIG. 37 is an enlarged detail view of area 37 of FIG. 34; with the ladder shown in a partially extended and partially folded position.

FIG. 38 is an enlarged detail view of area 38 of FIG. 27; with the ladder shown in a partially extended and partially folded position.

FIG. 39 is an enlarged detail view of area 39 of FIG. 32; with the ladder shown in a partially extended and partially folded position.

FIG. 40 is a reduced scale perspective view of the ladder of FIG. 1, with the ladder shown in a fully extended and open position.

FIG. 41 is a reduced scale front view thereof, with the ladder shown in a fully extended and open position.

FIG. 42 is a reduced scale rear view thereof, with the ladder shown in a fully extended and open position.

FIG. 43 is a reduced scale left-side view thereof, with the ladder shown in a fully extended and open position.

FIG. 44 is a reduced scale right-side view thereof, with the ladder shown in a fully extended and open position.

FIG. 45 is a top view thereof, with the ladder shown in a fully extended and open position.

FIG. 46 is a bottom view thereof, with the ladder shown in a fully extended and open position.

FIG. 47 is a reduced scale rear perspective view thereof, with the ladder shown in a fully extended and open position.

FIG. 48 is an enlarged detail view of area 48 of FIG. 40; with the ladder shown in a fully extended and open position.

FIG. 49 is an enlarged detail view of area 49 of FIG. 47; with the ladder shown in a fully extended and open position.

FIG. 50 is an enlarged detail view of area 50 of FIG. 47; with the ladder shown in a fully extended and open position.

FIG. 51 is an enlarged detail view of area 51 of FIG. 40; with the ladder shown in a fully extended and open position; and,

FIG. 52 is an enlarged detail view of area 52 of FIG. 47; with the ladder shown in a fully extended and open position.

The broken lines depict boundaries of the enlargements and portions of the ladder that form no part of the claimed design.
